UNITED STATES PATENT OFFICE

JOSIAH S. WILSON, OF LANARK, ILLINOIS.

WASHING-MACHINE.

SPECIFICATION forming part of Letters Patent No. 645,157, dated March 13, 1900.

Application filed September 11, 1899. Serial No. 730,073. (No model.)

To all whom it may concern:

Be it known that I, JOSIAH S. WILSON, a citizen of the United States of America, residing at Lanark, in the county of Carroll and 5 State of Illinois, have invented certain new and useful Improvements in Washing-Machines, of which the following is a specification.

My invention relates to certain improvements in washing-machines designed for the purpose of obtaining greater efficiency, ease in operation, durability, and simplicity.

To such end it consists in certain novel characteristics below described and the essential features of which are pointed out in the claims.

In the drawings, Figure 1 is a perspective of a complete machine. Fig. 2 is a vertical diametrical section in line 2 2 of Fig. 3, but showing the entire machine. Fig. 3 is a plan of the middle portion of the top of the cover with certain operating parts located thereon. Fig. 4 is a horizontal section of one of the washing-funnels, taken in line 4 4 of Fig. 5; 5 and Fig. 5 is a vertical diametrical section of said funnel.

Referring to the drawings, A is a suitable tub supported upon legs a and provided with a cover a', the cover being removably hinged to the tub by means of a concave lug a², adapted to hook into a stirrup a³. An ordinary hasp and staple a⁴ secures the opposite side of the cover. Upon the center of the cover is secured a bearing-plate a⁵, in the center of which is pivoted a revolving standard B, made up of two preferably symmetrical parts b b', secured together, as by bolts b², and embracing between them a vertically-reciprocating plunger-rod C and an oscillating segment D, the plunger-rod being guided vertically in the standard and being provided with teeth c, meshing with teeth d upon the segment. A handle E is adjustably secured to the segment by means of three holes e e' e³ 5 and two bolts e⁴ e⁵, the bolt e⁴ being passed through the hole e and the bolt e⁵ through either one of the holes e' e³, according to the position desired for the handle. The standard B has oppositely-projecting legs b³ b⁴, resting upon the margin of the plate a⁵ to

take the strain of the handle off of the bearing in the plate. The standard is secured against upward movement by means of a collar b⁵, fastened to the standard below the plate by means of a set-screw b⁶. The portion of the rod C which extends through the standard is preferably of such shape and cross-section as to make it non-rotatable in the standard, so as to keep the teeth of the rod in proper relation to those of the segment. 55 Upon the bottom of the rod is secured a spider F, having a boss f embracing the rod and secured thereto by means of a set-screw f'. Each arm of the spider bears a pounder G, consisting of a hollow cone g, secured to the 60 arm f² of the spider by means of a tube g', said tube extending down into the cone and being connected therewith at the bottom by means of a partition g². Below this partition is an inverted-cone-shaped wall g⁴, flaring at 65 the top g⁵ and uniting with the conical part g. Between the wall g⁵ and the partition g² is a valve H, having a stem h extending up into the tube g' and centering the valve over the opening below. 70

In operation the clothing is placed in the bottom of the tub and the pounders brought down upon it, sufficient water being present for the proper cleansing of the clothing. The oscillation of the handle E moves the pounders downward and upward, forcing the water through the clothing and effectually removing all dirt therefrom. 75

Upon the outside of the tub are a series of sockets I, in which are placed the downwardly-turned ends of two brackets J, embracing between them a bar K, adapted for the support of a wringer. 80

The above description is specific as to the construction shown; but it is not my intention to limit the invention absolutely thereto. 85

I claim as new and desire to secure by Letters Patent—

1. In a washing-machine, the combination with a suitable tub and cover, of a revolving standard mounted upon the cover, a vertically-reciprocating rod guided in the standard, a series of pounders supported by the bottom of the rod, a segment pivoted in the standard, intermeshing teeth upon the rod 90 to

and segment and a suitable handle for oscillating the segment to reciprocate the rod; substantially as described.

2. The combination with a suitable tub and cover, of a bearing-plate upon the cover, a standard, vertically pivoted in the bearing-plate and having arms adapted to rest upon the latter to take the strain from the bearing, a rod vertically and non-rotatably guided in the standard, a spider upon the rod, a series of washing-funnels upon the spider, a segment pivoted upon the standard, teeth upon

the rod and segment adapted to mesh with each other and a handle for oscillating the segment; substantially as described. 15

In witness whereof I have hereunto set my hand at Lanark, in the county of Carroll and State of Illinois, this 1st day of September, A. D. 1899.

JOSIAH S. WILSON.
